Primary Examiner — Sandra L Morris(74) *Attorney, Agent, or Firm* — Oliff PLC(57) **CLAIM**

The ornamental design for an accessory for robot toy, as shown and described.

DESCRIPTION

FIG. 1 is a front elevational view of the accessory for robot toy, the rear elevational view (not provided) being identical thereto;

FIG. 2 is a left-side elevational view thereof, the right-side elevational view (not provided) being identical thereto;

FIG. 3 is a top plan view thereof;

FIG. 4 is a bottom plan view thereof;

FIG. 5 is a front, right-side, top perspective view thereof; FIG. 6 is a cross-sectional view taken along line 6-6 in FIG. 3; and

FIG. 7 is a reference view showing the accessory for robot toy in use.

The broken lines depict environmental subject matter, and thus form no part of the claimed design.
